HOME FREEZER CABINET

Harland W. Whitmore, Kenosha, Wis., assignor
to Motor Products Corporation, Detroit, Mich.,
a corporation of New York

Application November 13, 1950, Serial No. 12,944

Term of patent 14 years

(Cl. D67—3)

To all whom it may concern:

Be it known that I, Harland W. Whitmore, a citizen of the United States of America, and a resident of the city of Kenosha, in the county of Kenosha and State of Wisconsin, have invented a certain new, original, and ornamental Design for a Home Freezer Cabinet, of which the following is a specification, reference being had therein to the accompanying drawing, forming a part thereof, wherein:

Fig. 1 is a front elevational view of a home freezer cabinet embodying my new design;

Figure 2 is an end view thereof, this end being substantially similar to the end not shown; and

Figures 3 and 4 respectively are sectional views taken on the lines 3—3 and 4—4 of Figure 1.

The characteristic feature of my design for a home freezer cabinet resides in the embossed ornamentation on the front panel as shown.

I claim:

The ornamental design for a home freezer cabinet, substantially as shown and described.

HARLAND W. WHITMORE.
